UNITED STATES PATENT OFFICE.

WILLIAM P. WAGE, OF BARRE CENTRE, NEW YORK.

SAD-IRON HEATER.

Specification forming part of Letters Patent No. 58,324, dated September 25, 1866.

To all whom it may concern:

Be it known that I, WM. P. WAGE, of Barre Centre, in the county of Orleans and State of New York, have invented certain new and useful Improvements in Sad-Iron Heaters; and I do hereby declare that the following is a full, clear, and exact description of the same, reference being had to the accompanying drawings and the letters of reference marked thereon.

My invention consists in the construction of a metallic stove, made portable, and to be heated by a lamp or gas, for the purpose of heating sad-irons. This device saves labor and time, and can be used in warm weather to the comfort of the persons employed in ironing.

In the drawings hereto annexed, and forming a part of this specification, A represents the stove, which is made of cast-iron, sheet-iron, or other suitable metal, in the form shown, whereby an air-chamber is formed between the upper casting, *m*, and lower casting, *n*. The castings *m* and *n* are level surfaces, the upper one, *m*, being provided with a small gutter, *c*, and a flange, *a*, near the outer edge and passing around three sides of the said casting or top. The lower casting, *n*, forms the bottom of the heater, being supported by suitable legs, and is provided with two or more small tubes, as seen at *H*, Fig. 2, which extend a slight distance beneath the casting and at the front portion of the stove.

B represents a sheet-iron case, which is provided with two or more oblong slots, *b*, and is placed within the gutter *c*, and secured by means

of the flange *a*. This case projects a suitable distance above the casting *m* to allow the sad-iron to be incased between said casting and the top of case B. The oblong slots *b* are to allow the handles of the iron to pass.

C represents the lamp, which is a metallic or other box or globe, provided with suitable burners, and placed beneath the casting *n*, so that the burners of the lamp may pass into the tubes *H*, heating the air-chamber.

xx are two or more windows made in the air-chamber, of isinglass, to regulate the heat of the lamps.

E is a chimney, which is set over a thimble upon the casting *m*, and passing above the case B, to carry the smoke from the air-chamber.

D are suitable handles, which are secured to the ends of the heater, to carry the same from place to place.

Having thus fully described my invention, what I claim as new, and desire to secure by Letters Patent, is—

The stove A, constructed, as described, with an air-chamber, provided with a metallic case, B, lamp C, and pipe E, substantially as and for the purpose herein set forth.

As evidence that I claim the foregoing I have hereunto set my hand in the presence of two witnesses.

W. P. WAGE.
